[57] CLAIM

The ornamental design for a toy airplane, substantially
as shown and described.

DESCRIPTION

FIG. 1 is a front perspective view of a toy airplane
illustrating my new design;
FIG. 2 is a top plan view thereof;
FIG. 3 is a side elevational view thereof, the side oppo-
site being substantially a mirror image;
FIG. 4 is a bottom plan view thereof;
FIG. 5 is a front elevational view thereof; and
FIG. 6 is a rear elevational view thereof.
